HENRY WINSLOW WHITE, OF COMMACK, NEW YORK.

ADHESIVE-APPLYING MECHANISM.

1,407,612.

Specification of Letters Patent. Patented Feb. 21, 1922.

Application filed October 1, 1920. Serial No. 414,077.

To all whom it may concern:

Be it known that I, HENRY WINSLOW WHITE, a citizen of the United States, residing at Commack, in the county of Suffolk and State of New York, have invented a new and useful Adhesive-Applying Mechanism, of which the following is a specification.

This invention relates to adhesive applying mechanisms more particularly those of the type used in depositing a narrow strip of paste or the like onto a moving web of paper or similar material. Such an operation is performed in machines such as bag-making machines and tube-making machines.

An ordinary mechanism for applying the strip of adhesive such as paste to a web of paper, has included a wheel partly submerged in a mass of fluid paste, and so disposed that friction between the web of paper and the periphery of the wheel causes the wheel to rotate becoming coated with paste and thereby transferring the paste onto the web, the amount of adhesive so transferred being regulated by a fixed scraper which functioned more or less satisfactorily in removing the excess paste from the coated wheel. Small lumps of adhesive are generally unavoidable, especially in paste. The paste is also an attraction for flies and other insects. The lumps of paste and the insects are carried by the wheel toward the scraper where they frequently become lodged and thereby prevent sufficient paste from getting onto the web. In machines operating at high speed, the imperfectly pasted seam appears in a large number of completed articles which may escape inspection.

It is an object of my invention, therefore, to provide adhesive applying mechanism in which an even amount of adhesive is applied without interference from foreign matter in the adhesive supply.

Another object of my invention is to provide an adhesive applying mechanism wherein the amount of adhesive to be applied can be closely regulated.

In the accompanying drawings I have shown, as an illustration of my invention, an embodiment of an adhesive applying mechanism such as I have found to be well suited for pasting the seam in a paper bag; but I desire that the drawings shall be considered as illustrating the invention rather than limiting it.

In the drawings Figures 1 and 2 are, respectively, an end elevational view and a side elevational view of the structure.

The web of paper A enters the machine as indicated and travels in the direction of the arrows. The web is wrapped part way about the surface of a cylindrical web-carrying roll 5 before it passes to the left into folding or other mechanisms (not shown). As the paper passes over the web-carrying roll 5 it is customary to apply a narrow strip of adhesive such as paste to the paper.

The shaft 6 which carries the roll 5 is provided near one end thereof with a gear 7 whose pitch diameter is equal to the diameter of the cylinder 5. A small idler 8 is supported on the main frame 9 below the gear 7 and a little to the right of shaft 6. A box or container 10, filled with paste 13, is also carried by the main frame below and to the right of the roll 5. A shaft 11 extends across the paste container 10 and is provided with a wheel 12 adapted to become coated with the adhesive, in the present instance paste, and with a gear 14 whose pitch diameter is equal to the outside diameter of the adhesive wheel 12. The gear 14 meshes with the idler 8 as indicated.

As the web of paper A is drawn into the machine it may rotate the web-carrying roll 5 in the direction of the arrow or this roll may be rotated by power otherwise supplied. The rotation of this roll will rotate the idler 8, the gear 14, and the adhesive-carrying wheel 12, in the direction indicated, giving the adhesive wheel 12 the same peripheral speed as the surface speed of the web-carrying roll 5. The adhesive wheel 12 will become heavily loaded with paste which is not scraped off as heretofore.

In order to transfer the proper amount of fluid paste from the heavily coated wheel 12 onto the moving web of paper I provide a paste transfer wheel 15 which is preferably slightly thinner than the adhesive-carrying wheel 12. The paste transfer wheel 15 is mounted to rotate freely between a pair of arms 16-17. The left ends of these arms are pivotally supported on an eccentric 18 carried on a shaft 19. An arm 20 fixed to the shaft 19, is provided with an arcuate slot 21 to co-operate with a stud 22 and wing nut 23 supported from the main frame of the machine.

The operator is able to adjust the position of the paste transfer wheel 15 by unloosening

ing the wing nut 23 and moving the arm 20 backwards or forwards as desired. This will result in shifting the axis of rotation of the transfer wheel 15 along the arcs $a-b$.
 5 The wheel 15 will be in frictional contact with either the paper A or the adhesive-carrying wheel 12 and will be rotated in the direction indicated by either one or the other of them. The amount of paste will depend, 10 however, upon the distance which separates the transfer wheel from the web or from the paste wheel. The range of adjustment is such that the wheel 15 may be moved entirely out of engagement with the web or the 15 paste-carrying wheel at will. It is desirable to prevent the transfer of paste at certain times especially when feeding in the paper or when the machine is standing idle.

The paste transfer wheel 15 picks up fluid 20 paste only from the heavily coated paste wheel 12, rejecting such foreign matters as lumps of paste, insects, etc., and provides an even, regular strip of paste so that the articles produced by the machine with which 25 it is associated are uniformly pasted.

While I have described this embodiment 30 of my invention in considerable detail, I desire to have it understood that this description is illustrative of the invention, for 35 it may undoubtedly be embodied in other specific structures within the scope of the appended claims.

What I claim is:

1. Adhesive applying mechanism comprising 35 a rotatably mounted adhesive wheel, a web-carrying roll, means for rotating the adhesive wheel, and a freely rotatable wheel to transfer adhesive from the adhesive wheel onto a web on said web-carrying roll, said 40 freely rotatable wheel being mounted on a shiftable axis.

2. Adhesive applying mechanism comprising 45 a rotatably mounted adhesive wheel, a web-carrying roll, means for rotating the adhesive wheel at the same peripheral speed as the surface speed of the web-carrying roll, and a freely rotatable wheel to transfer adhesive from the periphery of the adhesive wheel onto a web on said web-carrying roll, said 50 freely rotatable wheel being mounted on a shiftable axis.

3. Adhesive applying mechanism comprising 55 a rotatably mounted adhesive wheel, a web-carrying roll, means for rotating the adhesive wheel, a freely rotatable wheel to transfer adhesive from the adhesive wheel onto a web on said web-carrying roll, and means to move the axis of rotation of the 60 rotatable wheel to thereby adjust the amount of adhesive transferred.

4. Adhesive applying mechanism comprising 65 a rotatably mounted adhesive wheel, a web-carrying roll, means for rotating the adhesive wheel at the same peripheral speed as the surface speed of the web-carrying

roll, a freely rotatable wheel to transfer adhesive from the periphery of the adhesive wheel onto a web on said web-carrying roll, and means to move the axis of rotation of the rotatable wheel to thereby adjust the amount of adhesive transferred.

5. Adhesive applying mechanism comprising 75 a rotatably mounted adhesive wheel, a freely rotatable web-carrying roll, means for rotating the adhesive wheel in response to rotation of the web-carrying roll, and a freely rotatable wheel to transfer adhesive from the adhesive wheel onto a web on said web-carrying roll, said freely rotatable wheel being mounted on a shiftable axis.

6. Adhesive applying mechanism comprising 80 a rotatably mounted adhesive wheel, a freely rotatable web-carrying roll, means for rotating the adhesive wheel in response to rotation of the web-carrying roll and at 85 the same peripheral speed as the surface speed of the web-carrying roll, and a freely rotatable wheel to transfer adhesive from the periphery of the adhesive wheel onto a web on said web-carrying roll, said freely 90 rotatable wheel being mounted on a shiftable axis.

7. Adhesive applying mechanism comprising 95 a rotatably mounted adhesive wheel, a freely rotatable web-carrying roll, means for rotating the adhesive wheel in response to rotation of the web-carrying roll, a freely rotatable wheel to transfer adhesive from adhesive wheel onto a web on said web-carrying roll, and means to 100 move the axis of rotation of the rotatable wheel to thereby adjust the amount of adhesive transferred.

8. Adhesive applying mechanism comprising 105 a rotatably mounted adhesive wheel, a freely rotatable web-carrying roll, means for rotating the adhesive wheel in response to rotation of the web-carrying roll and at the same peripheral speed as the surface speed of the web-carrying roll, a 110 freely rotatable wheel to transfer adhesive from the periphery of the adhesive wheel onto a web on said web-carrying roll, and means to move the axis of rotation of the rotatable wheel to thereby adjust the 115 amount of adhesive transferred.

9. Adhesive applying mechanism comprising 120 a web-carrying roll, a container for adhesive, a driven adhesive wheel adapted to become heavily coated with adhesive from the adhesive container, and means comprising a freely rotatable wheel mounted on a shiftable axis to transfer a small amount of adhesive from the adhesive wheel onto a web on the web-carrying roll, said 125 means being incapable of transferring foreign materials.

10. Adhesive applying mechanism comprising 130 a web-carrying roll, a container for adhesive, a driven adhesive wheel adapted

to become heavily coated with adhesive from the adhesive container, and means to receive fluid adhesive from the coating on the adhesive wheel rejecting solid and semi-solid matter therein and depositing the fluid adhesive on a web on the web-carrying roll.

11. Adhesive applying mechanism comprising a web-carrying roll, a container for adhesive, a driven adhesive wheel adapted to become heavily coated with adhesive from the adhesive container, and means to receive an adjustable amount of fluid adhesive from the coating on the adhesive wheel rejecting solid and semi-solid matter therein and depositing the fluid adhesive on a web on the web-carrying roll.

12. The combination with a web-carrying roll, an adhesive container adjacent thereto, and an adhesive wheel in the adhesive container; of mechanism interconnecting the web-carrying roll and adhesive wheel to rotate the one from the other, and means independent of said interconnecting mechanism for transferring adhesive from the adhesive wheel onto a web on the web-carrying roll when the roll and wheel are rotated, said means including a freely rotatable wheel mounted on a shiftable axis.

13. The combination with a web-carrying roll, an adhesive container adjacent thereto, and an adhesive wheel in the adhesive container; of mechanism interconnecting the web-carrying roll and adhesive wheel to rotate the one from the other, means independent of said interconnecting mechanism for transferring adhesive from the adhesive wheel onto a web on the web-carrying roll when the roll and wheel are rotated, said means including a freely rotatable wheel mounted on a shiftable axis, and means to shift the axis whereby the adhesive transferring capacity of the aforesaid means is adjustable.

14. In combination, a web-carrying roll, an adhesive container, an adhesive wheel in the container adapted to become coated with adhesive when rotated in the same, a gear train between the web-carrying roll and the adhesive wheel, to rotate the latter at the same peripheral speed as that of the web-carrying roll, and a freely rotatable

wheel co-operating with both the web on the web-carrying roll and the adhesive wheel to transfer adhesive onto the web, said freely rotatable wheel being mounted on a shiftable axis.

15. In combination, a web-carrying roll, an adhesive container, an adhesive wheel in the container adapted to become coated with adhesive when rotated in the same, a gear train between the web-carrying roll and the adhesive wheel to rotate the latter at the same peripheral speed as that of the web-carrying roll, a freely rotatable wheel co-operating with both the web on the web-carrying roll and the adhesive wheel to transfer adhesive onto the web, and means to shift the axis of rotation of the last mentioned wheel whereby the amount of adhesive transferred is regulated.

16. In combination, a web-carrying roll, an adhesive container, an adhesive wheel in the container adapted to become coated with adhesive when rotated in the same, a gear train between the web-carrying roll and the adhesive wheel to rotate the latter at the same peripheral speed as that of the web-carrying roll, a freely rotatable wheel co-operating with both the web on the web-carrying roll and the adhesive wheel to transfer adhesive onto the web, a supporting member for the last mentioned wheel, and an eccentric for shifting said supporting member and the axis of the last mentioned wheel whereby the amount of adhesive transferred is regulated.

17. An adhesive applying mechanism comprising a support, a web-carrying roll rotatably mounted on the support, an adhesive container disposed adjacent the web-carrying roll, an adhesive-carrying wheel in the container adapted to be coated with adhesive when rotated therein, gearing interconnecting the web-carrying roll and adhesive-carrying wheel to rotate them at the same peripheral speed, an adhesive-transfer wheel between the web-carrying roll and the adhesive-carrying wheel, a supporting arm for the adhesive transfer wheel, an eccentric support for the arm, and means to position the eccentric and thereby adjust the adhesive-transfer wheel.

HENRY WINSLOW WHITE.
